No. 808,545.

PATENTED DEC. 26, 1905.

W. G. KEELER.

ELECTRIC RAILWAY SYSTEM.

APPLICATION FILED JUNE 16, 1905.

UNITED STATES PATENT OFFICE.

WILLIAM G. KEELER, OF PHILADELPHIA, PENNSYLVANIA.

ELECTRIC-RAILWAY SYSTEM.

No. 808,545.

Specification of Letters Patent.

Patented Dec. 26, 1905.

Application filed June 16, 1905. Serial No. 265,487.

To all whom it may concern:

Be it known that I, WILLIAM G. KEELER, a citizen of the United States, residing at Philadelphia, county of Philadelphia, and State of Pennsylvania, have invented a certain new and useful Improvement in Electric-Railway Systems, of which the following is a specification.

My invention relates to a new and useful improvement in electric-railway systems, and has for its object to provide improved means to pick up or take up the current from line-wire.

With this end in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a side elevation of an electric car and a portion of a road-bed equipped with my invention; Fig. 2, a longitudinal section through one of the contacts located in the road-bed; Fig. 3, a cross-section taken on the line 3 3 of Fig. 2; Fig. 4, a cross-section taken on the line 4 4 of Fig. 2.

The essential feature of my invention consists in equipping each electric car with an endless metallic cable or belt running over wheels located underneath each end of the car and journaled in bearings depending from the car. Said endless cable or belt may be in the form of a chain, solid wire, or a series of twisted wires, and the lower run of this cable or belt is adapted by its own weight to sag down and come in contact with contacts located in the road-bed an equal distance apart connected with an underground line-wire. It will be seen that the friction generated between the contacts and the cable or belt will be sufficient to hold the cable or belt practically stationary upon said contacts while the car travels forward, and thus there will be no sliding contact and friction will be done away with, as in case of shoes which slide either upon a third rail or over contacts, the cable or belt coming down in a vertical line upon the contact and remaining stationary in contact with said contact until the rearward end of the car is reached, when the cable or belt will then pass upward from the con-

tact and over the rearward pulley, it being understood that there will be always at least two contacts underneath the car at one time, so that the cable or belt will make contact 60 with one before leaving the other.

A represents the contacts located in the road-bed.

B is the belt or cable, which runs over pulleys C, loosely journaled at each end of the 65 car.

I do not wish to limit myself to any particular form of contact; but in Figs. 2, 3, and 4 I have shown a very desirable form, which consists of a contact-block D, which is protected by a shell E, said shell being slotted at the top at E', the lips of the shell upon each side of the slot being curved inward, so as to guide the belt or cable to the contact-block D. Said contact-block D is bolted to the cross-piece F, the ends of the cross-piece F being supported upon the shell in such a manner that the shell can be easily removed from the cross-piece. Said cross-piece F is also secured by means of the plate G to a tube H, 70 through which a branch wire I extends to the line-wire. The branch wire I is connected to the contact-block D. Of course it is understood that all parts are properly insulated 75 from one another.

A shield J is secured to the contact-block, which protects the parts underneath the same from moisture, and the shell E is supported a slight distance above the ties, so that any water entering through the slot E' 80 may easily flow off, the shell E being secured to the ties at each end by the standards K.

It will thus be seen that as the car travels forward the cable is always revolving around the pulleys C, and as the contact is reached 90 the cable or belt simply travels downward to the contact, and that portion of the cable or belt lying upon the contact will remain stationary with that contact until the rearward end of the car reaches the contact, when the 95 cable will simply pass upward out of contact in traveling around the rearward pulley C. Thus all friction between the contacts and means of picking up the current is avoided, 100 as in the case of shoes or rollers.

I have not shown any means for transferring the current from the cable or belt to the motor and the car, as that is not a part of my invention, and there are numerous ways in which this could be accomplished. Of course 110 it is understood that the upper run of the cable can be guided and supported by suit-

able intermediate pulleys, if so desired, and insulating supports can be placed in the road-bed between the contacts to keep the lower run of the cable or belt out of contact with the road-bed.

5 Of course I do not wish to be limited in any way to the exact construction here shown, as slight modifications could be made without departing from the spirit of my invention.

10 Having thus fully described my invention, what I claim as new and useful is—

In an electric-railway system, a series of contacts located in the road-bed an equal distance apart, the distance being less than the 15 length of the car, each contact connected to a line-wire, a flexible or pliable endless metallic

cable or belt arranged underneath each car, and passing over pulleys journaled at each end of the car, the lower run of said cable or belt adapted to lie upon the contacts by its own weight and remain stationary with said contacts as the car travels forward, a slotted shell arranged over each of the contact-blocks, the walls of the slot being curved in such a manner as to act as a guide for the cable. 20

25 In testimony whereof I have hereunto affixed my signature in the presence of two subscribing witnesses.

WILLIAM G. KEELER.
